HARRY E. FRY, OF NEW YORK, N. Y.

MOLD FOR RUBBER ARTICLES.

1,218,641.

Specification of Letters Patent. Patented Mar. 13, 1917.

Application filed April 24, 1915. Serial No. 23,686.

To all whom it may concern:

Be it known that I, HARRY E. FRY, a citizen of the United States, and a resident of New York, county and State of New York, have invented certain new and useful Improvements in Molds for Rubber Articles, of which the following is a full, clear, and exact description.

This invention relates more particularly to molds for the manufacture of rubber heels for shoes.

In the manufacture of heels or heels and soles combined, the mold comprises primarily three members as ordinarily constructed. The inner member has an opening therethrough shaped to correspond to the shape of the article to be made and on one side of the intermediate member is a top plate while the opposite face of the intermediate member is covered by a bottom plate. The molds are usually made so that a number of articles may be manufactured at the same time and the articles are usually vulcanized while held in the molds. It is desirable that the articles manufactured be identified with the name of the manufacturer or with the name of the dealer. One of the mold plates or members usually has such name or other identifying characters cut or otherwise produced thereon so that when the heel or other article is cast, the name or characters will appear on the heel. As ordinarily constructed the die or member containing the name is of heavy metal and there must be a name or other character for each mold, there being, as before stated, a number of these molds arranged along side of each other. If the articles manufactured are to contain the name of different manufacturers or dealers in shoes in connection with which the heels are used, it will be evident that the cost of the dies would be considerable because the plate or member containing the name of the manufacturer or dealer would either have to be changed with a new member or a special member prepared for the particular manufacturer or dealer.

One of the principal objects of the invention is to overcome the objections referred to and to provide simple and efficient means whereby the molds may be constructed substantially the same as heretofore, except that the name of the manufacturer or dealer or other identification character or characters is produced upon a thin metal or other member or matrix interposed between two of the

usual members of the mold thus avoiding the necessity for forming the names or characters directly upon one of the main members of the mold.

Another object of the invention is to provide a mold which is adapted to form various kinds of rubber heels or like articles with any desired character or characters thereon, and with very little expense.

With these and other objects in view, the invention will be hereinafter more particularly described with reference to the accompanying drawings, which form a part of this specification, and will then be pointed out in the claims at the end of the description.

In the drawings, Figure 1 is a fragmentary view of one section of the mold.

Fig. 2 is a plan view with the top member removed.

Fig. 3 is an enlarged transverse section, taken on the line III—III of Fig. 2; and

Fig. 4 is a fragmentary plan view of the name or character plate or member.

The mold 10 comprises a main or intermediate member 11, a top member 12 and a bottom member 13. These members are usually of steel and of considerable thickness and each member 11, 12 and 13 is of such a length as will permit a number of molds to be made at the same time. Only one mold section is provided and so far as the mold is concerned it may comprise a number of sections or only a single section. The member 11 is provided with a plurality of dowel pins or bolts 14 which are adapted to fit into openings in the members 11 and 12 so that the said members will register with respect to each other. The member 11 has an opening corresponding to the shape of the article to be made, in this case a rubber heel, and extending upward from the member 13 are posts or pins 16. The posts or pins 16 have a tapering top portion and a reduced part 17 adapted to form openings or recesses in the heel. The member 12 may have its surface or face provided with projecting parts 18 and 19 to properly shape one face of the heel. The parts as thus described may be of the usual or of any preferred construction.

Ordinarily the name of the manufacturer or dealer or other identifying characters are formed on or in the inner face of the member 13, and when a change in the name or the characters is made, the said member 13 is usually thrown away and another one

used therefor. To avoid this, I provide a mold or matrix member 20. This member 20 may be of any suitable material, as aluminum or other sheet metal or may be made of papier mâché, or from the material such as used in stereotyping. The member 20 has characters 20^a which are to be reproduced on the heels as manufactured and which may be made of any suitable nature. The metal member 20 is thin and may be such as will permit the characters 20^a to be produced thereon by means of type or dies or otherwise, and said member may have openings to fit over the posts 16 and with other openings 22 to fit the dowel pins in order that the said member may register properly with respect to the other members of the mold.

The member 20 is independent and detachable and is interposed between the member 13 and the member 11 and forms one face of the mold as shown. The rubber in a soft state is placed in the mold as indicated at 23 before the member 12 is placed in position, and when the article is completed the character or characters of the said member 20 will appear upon the rubber heel or other article made. In case a change of name or other characters, trade-marks, etc. are desired, it is only necessary to provide a new plate or member 20 which may be very readily done and at a very little expense, without disturbing the main members of the mold.

It will be evident from the foregoing that simple means is provided whereby rubber heels or like articles may be manufactured with different names or characters thereon without changing the molds or the main

members thereof; and that the mold as thus made is simple in construction and is just 40 as readily assembled and is less expensive than the molds as ordinarily constructed when made to accomplish the same results.

Having thus described my invention, I claim as new and desire to secure by Letters 45 Patent:—

1. In a mold of the character described, the combination with an intermediate member having an opening therethrough corresponding to the shape of the article to be 50 made, of a bottom member, and a character plate arranged between said intermediate and bottom members, the marginal portion of said plate being clamped between said members and the middle portion of said 55 plate forming one face of the mold.

2. In a mold of the character described, the combination with an intermediate member having an opening therethrough corresponding to the shape of the article to be 60 made, of a bottom member having posts projecting therefrom for engagement with the intermediate member, and a character plate arranged between said intermediate and bottom members, the marginal portion 65 of said plate having openings fitting around the posts on the bottom member and the middle portion of the plate forming one face of the mold.

This specification signed and witnessed 70 this 23rd day of April, A. D. 1915.

HARRY E. FRY.
